UNITED STATES PATENT OFFICE.

ANTONIO MISTRETTA, OF NEW YORK, N. Y.

TRIMMING ATTACHMENT FOR EMBROIDERY MACHINES.

Application filed October 3, 1925. Serial No. 60,263.

This invention relates to devices for stitching and trimming by means of an embroidering or sewing machine and more particularly to a special attachment permitting these 5 two operations to be performed at the same time using a machine of the character mentioned.

The invention more especially refers to improved devices for producing embroidery 10 work of the kind known as appliquéd embroidery or bonnaz embroidery, whereby the cost of manufacture of these products is lower than that entailed by methods heretofore in use.

15 The primary object of this invention is to provide a novel and improved arrangement for producing appliquéd or bonnaz embroidery work whereby considerable saving of labor may be effected while at the same time 20 work of a superior character may be produced.

Another object of this invention is to provide a simple and practical attachment for embroidery machines of the types now in use 25 for producing appliquéd embroidery, whereby the appliquéd part proper is trimmed by the machine at the same time that the stitching operation takes place, while the fabric serving as a base for the work is not affected by the trimming operation.

A further object is to provide a novel and improved attachment for embroidery machines of the character mentioned, consisting of relatively few parts and adapted also 30 to be used with minor modifications in connection with sewing machines, designed for ordinary and special purposes.

Other objects and advantages of the present invention will more fully appear as the 40 description proceeds and will be set forth and claimed in the appended claims.

This invention being more particularly directed to improvements in the production of appliquéd work, I will describe the same 45 in connection with this work although as stated, the invention is susceptible of being applied also for the trimming of ordinary stitched work.

By appliquéd or bonnaz embroidery is 50 meant that kind of work where a piece or panel of decorative fabric is attached to a piece of fabric by means of a stitch which follows a certain predetermined outline representing some object or flower or animal, or other decorative motive or design.

After the panel or appliquéd work proper

has become attached to the base fabric by means of the stitching, the same is trimmed all around the stitching leaving a certain margin, so that due to the difference between 60 the materials of which the panel part and the base fabric are respectively composed, many novel and artistic effects may be obtained.

The work is generally carried out in two distinct steps, the first step being the stitching according to the design which may have been previously printed on the panel part and the other step being the trimming of the same which is generally performed by hand by means of ordinary scissors. This 70 trimming operation is therefore, necessarily slow, due to the care which must be exerted in keeping the width of the margin uniform, and the result is not always perfect being largely dependent upon the ability of the 75 operator to correctly gauge the width of the margin all around.

The stitching operation proper as stated, which is determined by a design imprinted upon the material may obviously be carried 80 out either by moving the material in relation to the needle of the machine or else by causing the needle itself to follow the outline of the design. The latter is the principle more generally employed in machines used for 85 this kind of work, which are accordingly made with the guide casing of the needle bar movable and controllable by means of a hand lever within convenient reach of the operator.

90 By skillful maneuvering of this hand lever, the operator causes the guide casing and therefore the needle itself to follow the outline of the design to be produced, at the same time also causing angular movements of the needle bar around its own axis, so that the needle may always be in the same position relative to the direction of the line of the design at any instant. In other words, assuming that a certain diametral 95 cross line of the needle bar coincides at the start with the direction of the outline of the design, the needle bar is angularly displaced as the direction of said outline changes so as to always maintain the same diametral 100 cross line in the direction of the outline. This produces a uniform stitch that evenly and closely follows the outline of the work.

110 In order to decrease the labor involved by the production of this kind of work, I have conceived the idea of providing a machine with means for trimming the appliquéd part

of the work at the same time that the stitching is done, without interfering with the fabric used as a base material. An embodiment of my invention is illustrated in the accompanying drawing in which—

Fig. 1, is a side view in elevation of my improved trimming attachment as applied to an embroidering machine;

Fig. 2, is a front view in elevation of the same;

Fig. 3, is a rear view in elevation of the same;

Fig. 4, is a detail plan sectional view through line 4—4 of Fig. 2;

Fig. 5, is a detail plan sectional view through line 5—5 of Fig. 1;

Fig. 6, is a side view in elevation of a device illustrating my method of producing appliquéd embroidery and

Fig. 7, is a plan view of a finished piece of appliquéd embroidery illustrating the kind of work produced.

Referring to Fig. 7, 10 designates a piece of base material upon which is placed the material from which the appliquéd part of panel 11 is produced. Said appliquéd part is first stamped with an outline of the pattern desired, and this outline is followed by the needle producing the stitch 12, sewing together the base material and the appliquéd part. The appliquéd part is then trimmed around the outline of the stitching at 13, leaving a margin 14 of a uniform width all around. The outline of the design is followed by the needle by causing angular movements of the needle bar 16 about its own axis according to changes in the direction of the outline. In Figs. 1, 2, 3, the needle bar 16 is represented at the highest point of its reciprocating travel, at which point its lower end 17 still projects underneath the needle bar casing 15. The trimming attachment proper consists of a stationary blade 18, carried by a vertical stem 19 which is attached to a collar 20, loosely inserted over casing 15; so that said collar is rotatable in relation to said casing but is prevented from moving in an axial direction by some suitable means. Accordingly, the needle bar is free to move up and down but due to this device its angular movements about its own axis will be transmitted to collar 20 as will be explained. The device furthermore, comprises a movable blade 21, hinged at 22 to the rear end of blade 18, and operated to close or open the shearing device thus produced, as the needle bar moves down or up.

To this end, an upwardly extending member 23, is secured to the lower portion 17 of the needle bar by means of a screw 24 or in any other suitable manner. Said member 23, becomes therefore one with the needle bar, and participates in its reciprocating motion. The upper part 25 of said upward-

ly extending member is connected to the outer end 26 of movable blade 21 by means of a connection 27, so that the up and down motion of the needle bar will cause oscillating motion of said blade 21.

The upwardly extending member 23, has a vertical opening 28 through which passes stem 19 of the stationary blade, which is thus maintained in its vertical position. At the same time it will be observed that the angular movements of the needle bar which are shared by member 23 connected thereto, will be transmitted by said member 23 to stem 19 which is guided thereby, causing collar 20 to participate in said angular movements. The stationary blade is vertically adjustable in relation to the bed plate 29 of the machine, its upper part being provided with vertical slots as at 30, permitting the same to be fixed to part 20 by means of screws 31, so that the lower edge of blade 18 may be set at a greater or lesser distance from the top of the bed plate.

Said lower edge of the stationary blade is preferably parallel to the upper surface of the bed plate of the machine as shown, and the distance therebetween is adjusted to suit the thickness of the fabric which is used as a base in producing the appliquéd work.

During the downward stroke of the needle bar, the movable blade 21 is caused to swing downwardly, cutting the margin of the appliquéd part in correspondence with the stitch and of a width which is predetermined by the distance (a), between the needle and the cutting edge of the blades.

In order to increase the efficiency of my device, I prefer to insure a sharp cutting action by attaching connection 27 to the needle bar by means of a tension spring 32. Said spring 32 tends at all times to pull connection 27 inwardly, thus maintaining blade 21 in close adherence to blade 18, this action being comparable to the side pressure of one blade against the other, which is exerted by hand, when using an ordinary pair of scissors.

The arrangement described, causes the cutting device to be operated simultaneously with the needle and also causes the same to follow the angular displacement of the needle bar. Furthermore, by mounting the stationary blade so that the same is detached from the bed plate of the machine and vertically adjustable in relation thereto, it is possible to cut only one of the fabrics employed in producing the work while the other fabric is unaffected by it. This is particularly important in connection with appliquéd work since, as stated, only the appliquéd or panel part is trimmed while the base material is left untouched.

The method as applied to the production of appliquéd work is clearly illustrated in

Fig. 6, where the device is shown at the end of the downward stroke of the needle bar. In the same 10 designates the base material and 11 the material used to produce the panel or appliquéd part. From the drawing it is seen that the stationary blade is adjusted so that the base material can comfortably pass between the lower edge of the stationary blade and the top of the bed plate. The panel material is engaged by the trimming device, the outer end of the stationary blade being inserted between the base material and the panel material and the panel material being inserted between the stationary blade and the movable blade. It is therefore, obvious that the trimming of the appliquéd part or panel takes place simultaneously with the stitching, and that the width of the margin will be maintained uniform throughout.

The arrangement shown where the pivotal connection between the two blades is somewhat to the rear of the needle, permits of their cutting or active portion being located exactly in correspondence with the needle itself, so that the cutting operation always takes place at a point located on a line at right angle to the direction of the stitching at the point where the stitching takes place.

The device may be used practically unchanged in connection with an ordinary sewing machine where the needle bar guide casing is stationary and where the needle bar is capable of reciprocating up and down motion but is not capable of angular displacement. In this case the stitching is caused to follow the design by moving the fabric in relation to the needle instead of moving the needle in relation to the fabric. Therefore, it will be sufficient to cause reciprocating action of the movable blade, simultaneously with the reciprocating action of the needle bar in the manner outlined.

In a broad sense however, the method itself remains unchanged, its essential feature being the trimming of the appliquéd part independently of the base material as and when the stitching operation is performed. The width of the margin left around the stitch is usually always the same and therefore no means for adjusting the distance (a) between the needle and the cutting device are shown. It is obvious however, that suitable means for adjusting this distance may be provided if desired.

When there is a sudden change in the direction of the design outline, as for instance at 33 in Fig. 7, it may be convenient to stop the cutting operation somewhat behind the point where the change in the direction of the stitching takes place. In such cases, the operation is stopped before the point of sudden change is reached and the cutting device is rendered temporarily

inoperative in any suitable manner, for instance, by detaching connection 27 from the upwardly extending member 23 and attaching it to the needle bar guide casing 15, as shown in dotted lines at 25'. 70

Spring 32 may also be detached at the same time. Blade 21 of the cutting attachment will thus remain stationary, no longer participating in the reciprocating motion of the needle bar. In the same or in any other suitable manner, the cutting device may also, of course, be rendered inoperative at any time when it should be desired to operate the machine only for stitching and not for cutting. 75

However, the same object may also be attained merely by adjusting the height of the stationary blade from the bed plate of the machine so that the fabric or fabrics operated on may easily be inserted therebetween. 80

My invention may be carried into practice in ways differing from that shown without departing from the inventive idea; therefore, I reserve to myself the right to design and build devices of the character mentioned in any way or manner which may fairly enter into the scope of the appended claims. 85

I claim:

1. In a machine of the character specified, the combination with a needle bar capable of axial reciprocating motion and capable of angular movement about its own axis, and an axially stationary member coaxial therewith and adapted to rotate therewith, of a stationary blade mounted on said member, a movable blade hinged thereto, and means associated with said needle bar causing oscillating motion of said movable blade. 90

2. In a machine of the character specified, the combination with a needle bar capable of axial reciprocating motion and capable of angular movement about its own axis, and an axially stationary member coaxial therewith and adapted to rotate therewith, of a stationary blade adjustably mounted on said member, a movable blade hinged thereto and means associated with said needle bar causing oscillatory motion of said movable blade. 100

3. In a machine of the character specified, the combination with a needle bar capable of axial reciprocating motion and capable of angular movement about its own axis, and an axially stationary member coaxial therewith and adapted to rotate therewith, of a stationary blade mounted on said member, a movable blade hinged thereto and an articulated connection between said needle bar and said movable blade. 110

4. In a machine of the character specified, the combination with a bed plate, a needle bar capable of reciprocating motion to and from said bed plate, and capable of angular movement about its own axis, and an axially 120

95

105

110

115

125

130

stationary member coaxial with said needle bar and adapted to rotate therewith, of a stationary blade mounted on said member so as to be adjustable to and from said bed plate, a movable blade hinged thereto, and an articulated connection between said needle bar and said movable blade.

5. In a machine of the character specified, the combination with a needle bar capable of axial reciprocating motion and capable of angular movement about its own axis, and an axially stationary member coaxial with said needle bar and adapted to rotate therewith, of a stationary blade mounted on said member, a movable blade hinged thereto at a point out of lateral alignment with the axis of said needle bar, and an articulated connection between said needle bar and said movable blade, causing shearing action of said two blades at a point in lateral alignment with the axis of said needle bar.

6. In a machine of the character specified, the combination with an axially reciprocating needle bar capable of angular movement about its own axis, an axially stationary member coaxial and adapted to be angularly moved therewith, and a stationary needle bar guide casing, of a stationary blade mounted on said member, a movable blade hinged thereto, and an articulated connection between said needle bar and said movable blade.

7. In a machine of the character specified, the combination with a bed plate, a needle bar axially movable to and from said bed plate and capable of angular movement about its own axis, an axially stationary

member coaxial and adapted to be angularly moved therewith, and a stationary needle bar guide casing, of a stationary blade, mounted on said member so as to be adjustable to and from said bed plate, a movable blade hinged thereto, and an articulated connection between said needle bar and said movable blade.

8. In a machine of the character specified, the combination with a needle bar capable of axial reciprocating motion and capable of angular movement about its own axis, and an axially stationary member coaxial and adapted to rotate therewith, of a stationary blade mounted on said member, a movable blade hinged thereto, and means associated with said needle bar causing oscillating motion of said movable blade and transmitting angular movements of said needle bar about its own axis to said stationary blade and rotatable member.

9. In a machine of the character specified, the combination with a needle bar capable of axial reciprocating motion and capable of angular movements about its own axis, and an axially stationary member coaxial and adapted to rotate therewith, of a stationary blade depending from a stem mounted on said member, a movable blade hinged thereto, and a member inserted over said stem and associated with said needle bar causing oscillating motion of said movable blade and transmitting to said stem and rotatable member angular movements of said needle bar about its axis.

ANTONIO MISTRETTA.
